(57) **CLAIM**

The ornamental design for a food pouch, as shown and described.

DESCRIPTION

FIG. 1 is a top, front, perspective view showing an embodiment of a food pouch.

FIG. 2 is a front and back view of the food pouch of FIG. 1.

FIG. 3 is a side view of the food pouch of FIG. 1.

FIG. 4 is a top view of the food pouch of FIG. 1; and, FIG. 5 is a bottom view of the food pouch of FIG. 1.

The broken line showing of portions of the food pouch is included for the purpose of illustrating environmental structure and forms no part of the claimed design.
